APPARATUS FOR LOCATING AND TRACING CONDUCTIVE STRUCTURES

Thomas G. Humphreys, Jr., 2245 Pine Crest Drive,
Birmingham, Ala. 35216

Filed Nov. 7, 1968, Ser. No. 14,349

Term of patent 14 years

Int. Cl. D10—11

U.S. Cl. D52—6

FIG. 1 is a side elevational view of my apparatus for locating and tracing conductive structures.

FIG. 2 is a plan view thereof looking from the top of FIG. 1;

FIG. 3 is an end view thereof looking from the right of FIG. 1;

FIG. 4 is a bottom plan view showing the opposite side of the apparatus from that shown in FIG. 2;

FIG. 5 is a side elevational view showing the opposite side of the apparatus from that shown in FIG. 1; and,

FIG. 6 is an end view showing the opposite end of the apparatus from that shown in FIG. 3.

I claim:

The ornamental design for an apparatus for locating and tracing conductive structures, as shown.
